UNITED STATES PATENT OFFICE.

DENNIS HOWARTH, OF CHESTER, PENNSYLVANIA.

DESIGN FOR TEXTILE FABRIC.

SPECIFICATION forming part of Design No. 30,927, dated May 30, 1899.

Application filed May 1, 1899. Serial No. 715,244. Term of patent 3½ years.

To all whom it may concern:

Be it known that I, DENNIS HOWARTH, a citizen of the United States, residing at Chester, in the county of Delaware and State of Pennsylvania, have invented and produced a new and original Design for Textile Fabrics, of which the following is a specification, reference being had to the accompanying drawing, forming part thereof.

10. The drawing is a top view of a piece of textile embodying my design.

As shown in the drawing, the leading or material feature of my design consists of a series of parallel comparatively broad stripes alternated by a group of parallel stripes gradually diminishing in thickness toward the center of the group and a very broad stripe arranged in the center of the group. The stripes 15, as will be seen, are comparatively broad

and of the same thickness throughout their 20 length. The stripes in the group 2, as will be seen, gradually diminish in thickness toward the center of the group—that is to say, each stripe is of the same thickness throughout its length, but each succeeding stripe is 25 of less width than the preceding one. These stripes are grouped, as shown, parallel with a very broad stripe, which forms the center of said group.

Having described my invention, what I 30 claim as new, and desire to secure by Letters Patent, is—

The design for textile fabric, as herein shown and described.

DENNIS HOWARTH.
